UNITED STATES PATENT OFFICE.

ALVIA K. BROWN, OF NEWTON, IOWA.

GARBAGE-DESTROYER.

SPECIFICATION forming part of Letters Patent No. 338,134, dated March 16, 1886.

Application filed April 18, 1885. Serial No. 102,692. (No model.)

To all whom it may concern:

Be it known that I, ALVIA K. BROWN, a citizen of the United States, residing at Newton, in the county of Jasper and State of Iowa, 5 have invented certain new and useful Improvements in Garbage-Destroyers; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 Figure 1 of the drawings is a representation of a vertical longitudinal section. Fig. 2 is a horizontal section of the cylinder.

20 My invention relates to garbage-destroyers; and it consists in the construction and novel 25 combination of parts, as will be hereinafter fully described, and particularly pointed out in the claims.

25 Referring by letter to the accompanying drawings, *d* designates a furnace, of which *d'* is the grate-bars and *e* the ash-pit.

30 *C* designates a vertical cylinder or reservoir, which extends above the top of the brick-work of the furnace, and extends also down nearly to the grate *d'*, and this cylinder 35 *C* is provided in its lower end with an inclined dumping-grate, *e*, having a dumping-rod, *c'*, connected therewith to be used for dumping the contents of the reservoir.

35 *a* designates a hopper, through which the 40 garbage is fed to the cylinder, the bottom of this hopper being provided with a dumping-valve, *b*, to control the supply of the garbage 45 to the cylinder. Just above the dumping-valve *b* the hopper is tapped by a pipe, *m*, having a stop-cock, *m'*, which pipe is 50 designed to convey the water from the garbage in the hopper into the sewer by natural drainage before the garbage is admitted to the cylinder to serve as fuel.

45 *G* designates a second smaller furnace, having a grate *G'* which is connected with the furnace *d* and the boiler *h* by the pipe *f*.

55 *C'* designates a gas-pipe in the vertical cylinder *C*, which conveys the gas generated in

the upper portion of the cylinder *C* to the 50 fire on the fire-grate and aids combustion.

I designates a pipe which connects the cylinder *C* with the smoke-stack *J*, said pipe *I* being provided with a stop-cock, *K*, by which the steam generated in the cylinder *C* may 55 be permitted to escape by way of the smoke-stack.

h designates an ordinary steam-boiler, which is connected with the furnaces and is designed to supply steam generated by the garbage-fuel for any desired purpose.

I have illustrated a bridge, *L*, having inclined approaches, and a trap, *L'*, so that the garbage may be dumped directly from a cart into the hopper; but the bridge may be dispensed with and the garbage fed to the hopper in any manner desired.

The gas-pipe *C'* extends from the top of the cylinder down through the dumping-grate at the bottom of the cylinder nearly to the 70 fire-grate.

The dumping-grate may be made so as to dump from the center, and is operated by a rod extending through the furnace-wall. By this construction it will be seen that after the 75 liquid matter has been removed from the garbage in the funnel *a* it may be dumped into the reservoir *C* by simply drawing the slide-valve *b*, and is then consumed by the fire beneath the said cylinder.

80 The particles of combustion will be delivered to the boiler by means of the pipe *f*, and the secondary furnace will serve to heat the said pipe and consequently the particles of combustion therein until carried into the 85 boiler.

Having thus fully described my invention, what I claim, and desire to secure by Letters Patent of the United States, is—

1. The combination, with the furnace *d*, 90 and the cylinder having the valved feeding-hopper, dumping-grate, and gas-pipe *C'*, of the secondary furnace, the boiler, smoke-stack, and the valved steam-pipe connecting the cylinder and smoke-stack, substantially as 95 specified.

2. A garbage-destroyer consisting of a main furnace, a reservoir in the top thereof, and

having a dumping-grate at its lower end, a steam-boiler, a secondary furnace interposed between the main furnace and the steam-boiler, and a pipe passing through the secondary furnace and connecting the boiler with the main furnace, whereby garbage placed in the reservoir may be consumed and the hot air and particles of combustion utilized to heat the boiler, substantially as specified.

In testimony whereof I affix my signature in the presence of two witnesses.

ALVIA K. KROWN.
